UNITED STATES PATENT OFFICE.

EVANS N. HARRIS, OF FRAZER, MISSOURI.

RAILWAY-RAIL TIE AND RAIL-FASTENER.

1,110,778.

Specification of Letters Patent. Patented Sept. 15, 1914.

Application filed December 17, 1913. Serial No. 807,274.

To all whom it may concern:

Be it known that I, EVANS N. HARRIS, citizen of the United States, residing at Frazer, in the county of Buchanan and State of Missouri, have invented certain new and useful Improvements in Railway-Rail Ties and Rail-Fasteners, of which the following is a specification.

This invention relates to improvements in railway ties and rail fasteners, of the class wherein the tie is formed wholly of metal bent to the required shape, and has for one of its objects to improve the construction and increase the efficiency and utility of devices of this character.

Another object of the invention is to provide a simply constructed device whereby the fastening devices may be adjusted to rails of various sizes and forms without material structural change, and wherein the rails are firmly clamped in position and effectually prevented from spreading or being otherwise displaced.

With these and other objects in view the invention consists in certain novel features of construction as hereinafter shown and described and then specifically pointed out in the claims, and in the drawings illustrative of the preferred embodiment of the invention—

Figure 1 is a plan view of a portion of one of the improved ties and the rail fastener with a portion of a rail arranged thereon. Fig. 2 is a section on the line 2—2 of Fig. 1. Fig. 3 is a side elevation of a portion of a tie with the rail fastener applied thereto. Fig. 4 is an end elevation of the improved tie and one of the rail fasteners with a section of rail arranged thereon. Fig. 5 is a detached perspective view of one of the rail engaging combined holding and brace members.

Corresponding and like parts are referred to in the following description and indicated in all the views of the drawings by the same reference characters.

The improved tie is constructed from a single plate of metal bent into the required shape. The tie may be of any required length or dimensions, but will generally be the same size as an ordinary tie, about 8 ft. long, 6 in. high and 10 in. wide, but these dimensions may be varied as required.

The improved tie comprises a body including a base or lower portion 10 and an upper or bearing portion 13 extending in parallel

relation, and vertical webs 11—12 spaced apart. At their edges the webs 11—12 are bent laterally into parallel relation to the body members, all but one of the laterally bent portions of the webs being integral with the body members, while the remaining laterally bent portion is fastened as at 19 to one of the body members, for instance the body member 13, as represented in Fig. 4. By this means a very compact and durable tubular tie structure is produced which requires no other fastening devices except the single row of rivets 19.

The tie is constructed from a single plate of metal bent into the required shape, and can thus be inexpensively manufactured, and is very strong and durable as the parts mutually brace and support each other. The rails, indicated conventionally at 22, bear transversely of the member 13, and bearing over the ties are combined stops and brace members 23 and secured to the ties by rivets or other similar suitable fastening devices 24. By this means the rails are effectually prevented from spreading, and held firmly in position. The upper member 13 of the tie is provided with longitudinal slots 25 externally of the stop members 23 and likewise provided with longitudinal slots 26 spaced inwardly from the slots 25. Disposed within the interior of the tie and between the webs 11—12 are rail engaging devices including base members 27—28 having depending lugs 29—30 through which a clamp member 31 extends, each clamp member having a head 32 at one end and a nut 33 at the other end engaging respectively against the outer faces of the lugs. By this means the members 27—28 together with their lugs 29—30 may be forcibly drawn toward each other.

Rising from the base member 27 is an integral rail flange engaging member 34 which extends through the slot 25 and bears over the upper face of the flange of the rail at one side of the web. Rising from the base 28 is another flange engaging member 36 which extends through the slot 26 and bears over the upper face of the flange of the rail at the other side of the web. The members 34—36 are spaced from the inner ends of the lugs 29—30 so that the inner ends of the lugs bear beneath the upper portion 13 of the tie and coact with the portions 34 and 36 to firmly support and clamp the rail in position and prevent it from displacement rela-

tive to the tie. The base portions 27-28 of the rail holding devices are wider than the slots 25-26, and thus bear at their sides beneath the underface of the bearing member 13 and are prevented from upward movement thereby, while the flange engaging members 34-36 bearing upon the upper faces of the flanges of the rail coat with the lugs 29-30 and effectually prevent any 10 downward or upward movement of the flange engaging members and the rails. The upper faces of the flanges being inclined downwardly and outwardly from the web, the inward movement of the holding members caused by the operation of the clamp device 31 produces a strong downward pressure upon the rails and binds them firmly to the ties. 15 The improved device is simple in construction, effectual in operation, and supports the rail without the necessity for using spikes, or clamp devices other than the members 31. The improved device can also be readily disconnected for replacing broken or impaired parts, or for releasing the rail when required.

Having thus described the invention, what is claimed as new is:

1. A metal railway tie formed from a single plate bent to shape and including body members extending in parallel relation, and vertical webs, the webs being directed outwardly at their edges and extending in parallel relation with the body members, and fastening means uniting one out-turned edge with one of the body members.

2. A metal railway tie formed from a single plate bent to shape and including body members extending in parallel relation, and vertical webs spaced apart, the webs being out-turned at their edges and extending in parallel relation with the body members, all

but one of the laterally directed portions being integral with the body members, and fastening means uniting the remaining out-turned portion with one of the body members.

3. A metal railway tie formed from a single plate bent to shape and including upper and lower members continuous from side to side and from end to end and extending in parallel relation and vertical webs spaced apart, the webs being out-turned at their edges and extending in parallel relation to the upper and lower members.

4. A metal railway tie formed from a single plate bent to shape and formed with a bottom, vertical webs spaced apart and a top, the webs being out-turned at their lower edges and extending in parallel relation to the bottom and out-turned at their upper edges and extending in parallel relation to the top, and fastening means uniting one out-turned edge of one of the webs to the top.

5. A metal railway tie formed from a single plate bent to shape and formed with a bottom, vertical webs spaced apart and a top, the webs being out-turned at their lower edges and extending in parallel relation to the bottom and out-turned at their upper edges and extending in parallel relation to the top, rail engaging stops bearing over said top, and fastening devices extending through said rail engaging stop and through the top of the tie and the out-turned edges of the webs.

In testimony whereof I affix my signature in presence of two witnesses.

EVANS N. HARRIS. [L. s.]
